UNITED STATES PATENT OFFICE.

JACOB D. SCHAKEL, OF CHICAGO, ILLINOIS, ASSIGNOR TO ELEVATOR COMPANY OF AMERICA, OF CHICAGO, ILLINOIS, A CORPORATION OF ILLINOIS.

LEVELING ATTACHMENT FOR ELEVATOR-CAR SWITCHES.

Application filed September 12, 1924. Serial No. 737,364.

My invention relates to switches, and more particularly to a leveling attachment for elevator car switches.

It is a purpose of my invention to provide 5 a switching device for use in controlling the movements of a body that moves in a fixed path such as an elevator moving up and down in a shaft. In certain cases it is very desirable to have the moving body such as 10 the elevator remain at a predetermined point or station for an extended period of time and to also cause said body to stop precisely at said station when a stop is to be made thereat. This is particularly desirable 15 in the case of elevators that are used for the purpose of hauling freight, where a wheeled vehicle is to be moved from a fixed level such as a floor on to a moving platform such as an elevator or off the elevator platform on to 20 the floor. In such cases it is very desirable that the elevator and the floor lie in the same plane or that the elevator is exactly level with the floor.

It is a purpose of my invention to provide 25 new and improved means associated with a moving body such as an elevator for accomplishing this purpose whereby substantially no changes are necessary in the equipment 30 of the elevator and the leveling device is merely in the form of an attachment to the previously provided mechanism. Electric elevators are ordinarily operated by a switch mechanism in the car that is to be actuated manually by the operator to cause the car to 35 move in either direction or to stop as desired. The mechanism in the car is ordinarily known as a car switch and is associated with certain controlling devices that are located at a remote point from the car, but 40 near the motor for operating the same so that actuation of the car switch will cause operation of the controlling means in a proper manner to move the car in the desired direction or to automatically stop the car 45 when the power is shut off. The standard devices for this purpose are not involved in the present invention and are not altered in any way in carrying out the purpose of this invention.

It is a purpose of my invention to provide 50 suitable switch closing mechanism that is actuated by the movement of the car or other movable body to operate the switch ordinarily provided in the ordinary manner, the operation thereof operating the motor in the 55 usual manner through the usual controller provided in connection with the switch adjoining the motor.

More particularly, it is a purpose of my invention to provide a switch for operating 60 an elevator or similar moving body that moves in a fixed path in opposite directions comprising stationary contacts and a pair of moving contact members co-operating with 65 said stationary contacts, certain of said stationary contacts controlling the movement of the car or body in one direction and the other of said contacts controlling the movement of the body or car in the opposite direction. 70

It is still a further purpose of the invention to provide a device of the above mentioned character in which one of said movable contact members is manually operable 75 and the other of which is mechanically operable independently of said manually operable means.

It is still another purpose of the invention to provide a mechanically operated 80 movable contact member operating means controlled by the movement of the car or body. The contacts of the switching device are connected up with suitable contacts on a standard controller and the controller is provided with suitable mechanism whereby 85 it is impossible for the manually operated switching member and the mechanically operated switching member to close two circuits for operating the motor in opposite directions, this being a standard construction 90 which is well-known in the art and which is not involved in the present invention.

In the embodiment of the invention shown in the drawings, the car switch comprises 95 stationary contact members having contact portions mounted on the opposite sides of an insulating base or support with a movable contact member mounted on one side.

of said support co-operating with the contact portions on that side of said support and a movable contact member mounted on the other side of said support, the contact portions opposite each other being electrically connected together. The manually operable movable contact member is operated by a handle mounted on a shaft that rotates or turns with the movable contact member that is manually operated. The mechanically operated movable contact member is freely rotatable on said shaft and is operated by means of a lever, the movement of which in one direction moves the movable contact member in the direction to close a circuit for moving the body in one direction and the movement thereof in the opposite direction moves the movable contact member into a position to close the circuit for moving the body or car in the opposite direction.

The lever is provided with a pair of rollers, one of which co-operates with a cam so mounted in the path of movement of the car or other movable body that when said roller engages therewith, the lever is moved in the direction toward the station or floor level with which it is desired to align the movable body or car and the other of which co-operates with a cam on the opposite side of the station or floor level referred to for moving the lever in such a direction as to cause movement of the car in the opposite direction to that when the first mentioned roller engages with its cam or also toward the station or floor level.

It is still a further purpose of the invention to provide means for maintaining the movable contact member that is mechanically operated or controlled by the position of the car normally in an open circuit position, said means also maintaining the lever carrying the rollers in a central position.

Other objects and advantages of the invention will appear as the description of the accompanying drawings proceeds. However, I desire to have it distinctly understood that I do not intend to limit myself to the details shown or described, but that I intend to include as part of my invention all such obvious changes and modifications of parts as would occur to a person skilled in this art and as would fall within the scope of the claims.

55 In the drawings:

Fig. 1 is a view partly in front elevation and partly in section of my improved switch mechanism;

Fig. 2 is a view partly in side elevation and partly in transverse section of said switch mechanism, portions thereof being broken away, the manually operable switch mechanism being shown principally in section, the section thereof being taken on line 2-2 of Fig. 1 and the mechanically op-

erated switch mechanism being shown principally in elevation;

Fig. 3 is a face view of my improved car switch with a portion of the cover broken away;

Fig. 4 is a fragmentary front elevational view of the movable contact operating lever and parts associated therewith; and

Fig. 5 is a fragmentary sectional view taken substantially on the line 5-5 of Fig. 1.

Referring in detail to the drawings, my improved switch mechanism is shown as being mounted on a suitable support 10 which may be a portion of an elevator car, said switch mechanism comprises a casing 11 which is provided with a cover 12 that is removable therefrom. The casing 11 is provided with a bearing portion 13 for a shaft 14 that projects rearwardly through said casing as will be clear from Fig. 2. The shaft 14 is provided with an enlarged or thickened square portion 15 that has a socket portion 16 provided in the end thereof into which the bearing stud 17 on the cover 12 projects.

Mounted in fixed position within the casing 11 is a plate of insulating material 18 upon which is mounted a plurality of contacts having the contact portions 20, 21, and 22 on one side of said insulating plate or support 18 and the contact portions 24, 25, and 26 on the other side of said plate or support 18. Suitable conducting securing members such as the bolts 27 connect the members on the opposite sides of the insulating member 18 in pairs, that is, the contact portion 20 is connected with the contact portion 24 so as to form what is in effect a single contact and in a similar manner the contact portions 21 and 25, and 22 and 26 are connected together on opposite sides of the insulating base member 18 so that each pair of said contact portions is in effect a single contact member. Blocks of insulating material 19 and 23 are also provided, said members 19 and 23 being connected together by bolts 27 and spacing sleeves 28 are provided between the members 19 and 23 and the plate 18 to space the same therefrom. The contacts 20, 21, 24, 25, 22, and 26 lie directly against the insulating base member 18, the member 20 being provided with an arcuate flange 29, the member 21 with an arcuate flange 30, the member 22 with an arcuate flange 31, the member 24 with an arcuate flange 32, the member 25 with an arcuate flange 33 and the member 26 with an arcuate flange 34.

All said flanges are curved on a center corresponding to the axis of the shaft 14. The shaft 14 extends through the base member or base plate 18 and has mounted thereon on the thick squared portion 15, a movable contact member 35 which is made in halves as shown in Fig. 3, each portion

70

50

100

105

110

115

125

129

thereof being provided with a clamping member 36 adapted to engage with the squared portion 15 of the shaft, an insulating bushing 37 being provided between said clamping portion 36 and the shaft portion 15. Suitable clamping members 38 pass through the clamping portions 36 to clamp the member 35 tightly on the shaft 14. The member 35 is provided on one arm thereof with a socket portion 39 within which is seated a contact member 40 in the form of a block of conducting material such as carbon, which is projected outwardly by means of the coil spring 41 so that the member 40 will bear against the block 19 and against the flanges 29 and 30 of the contacts 20 and 21 as the shaft 14 is turned. The other half of the member 35 is provided with a double socket member 42 having a pair of bores for receiving the contact members 43 of suitable conducting material such as carbon which are projected outwardly by means of the coil springs 44 seated in the bores in the member 42. Said members 43 are held in engagement with the arcuate flange 31 of the member 22 by the action of the coil springs 44.

In order to provide for the ready replacement of the contact members, the socket portions of the member 35 are provided with removable cover members 45 and 46 which are held respectively in position by means of the screws 47 and 48.

The block 19 is a dead contact, but the contacts 20, 21 and 22 are connected with suitable terminals on a standard controller so that when the contact member 35 bridges the contacts 20 and 22, the elevator will be moved in one direction and when the contact member 35 bridges the contacts 21 and 22, the elevator will be moved in the opposite direction.

The contacts 113 are also provided and when the contact member 43 at the right of Fig. 3 engages with the contact 113 at the right thereof, the contacts 20 and 113 are bridged by the contact member 35 to operate the elevator at a higher speed than when the contacts 20 and 22 are bridged. As there are no resistances in series with the contacts 113, and due to the fact that the other contact 43 is in engagement with the contact member 22 which has resistances in series therewith on the controller, the current will flow through the contact 43 that is in engagement with the contact 113. In a similar manner, if the movable contact member is moved to such position that the contact member 43 at the left of Fig. 3 engages with the contact 113 at the left of Fig. 3, the contacts 21 and 113 will be bridged by the member 35 and the elevator will be operated at high speed in the direction opposite to that when the contacts 20 and 113 are bridged by the member 35.

On the opposite side of the insulating

member 18 from the movable contact 35, is a movable contact member 49, said movable contact member 49 is provided with a hub portion 50 that is freely rotatably mounted on the shaft 14. The member 49 is provided with removable cap portions 51 on opposite ends thereof which are held in place by means of the bolts 52 and which are provided with hollow bosses 53 within which are slidably mounted the contact members 54 which are each made of a block of carbon or similar conducting material, said members being projected outwardly by means of the coil springs 55 mounted in the bores 53. The contact members 54 engage with the dead contact 23 and with the flanges 32 and 33 on the live contacts 24 and 25 and with a flange 34 on the live contact 26.

The caps 51 are insulated from the member 49 by means of the sheet of insulating material 56 and the flanged insulating sleeves 120 are mounted in the openings in the ears 121 that receive the bolts 52 and under the heads 122 of said bolts. The conductor 123 connects the caps 51 preferably being held clamped under the nuts mounted on certain of the bolts 52 provided on said members 51 as will be clear from Fig. 1.

The shaft 14 is actuated by means of the handle 57 which is connected with the lever 58 by means of a shaft 59 and which carries the finger 60 that is adapted to engage between a pair of stops 61 when the lever 58 is in a central position to retain the same in such position.

A coil spring 115 is mounted on a lug 116 on the handle 58 and urges the member 60 toward the casing 11, the member 60 being pivoted at 117 as shown in Fig. 2. A collar 118 is slidably mounted on the shaft 59 and 119 engages with the end 119 of the finger 60 which also is slidably mounted on the shaft 59.

The lever 58 is provided with a hub portion 62 which is secured to the shaft 14 so as to turn therewith. Accordingly, by actuation of the sleeve 118 by moving the same toward the lever 58 and then swinging the lever 58 either to the right or left, the finger 60 is moved out from between the stops 61 and the shaft 14 will be rotated to either 115 bridge the gap between the contacts 20 and 22 or the contacts 21 and 22.

Mounted on the member 49 spaced from the shaft 14 is a pivot pin 63 to which is pivotally secured the link 64, the other end 120 of which is pivotally mounted on the pivot pin 65 which is mounted between the bifurcations 66 provided on the end of the lever 67 which is keyed on a shaft 68 that extends through a bearing 69 provided on a lateral extension 70 of the casing 11. Suitable collars 71 and 72 are provided on opposite sides of the bearing 69 so as to hold the shaft 68 from axial movement in said bearing. The shaft 68 also has keyed thereon a lever 73 130

which is pivotally mounted on a pivot pin 74 which is mounted in the bifurcation 75 provided on the member 76 which is mounted on the end of the link 77. The link 77 is provided on the opposite end thereof with a bearing member 78 having pivot ears 79 through which extends the pivot pin 80 for pivotally connecting the end of the lever 81 thereto. The lever 81 is pivotally mounted on a pivot pin 82 provided on the bracket 83 which is mounted on a suitable support 84 provided on the moving body such as the elevator upon which the switching mechanism is mounted and the movement of which the switching mechanism controls.

The lever 81 is provided with a pair of arms 85 and 86 upon which are mounted the rollers 87 and 88. The roller 87, it will be noted, extends on one side of the arm 85 and the roller 88 extends on the opposite side of the arm 86, said rollers being mounted to rotate respectively on the shafts 89 and 90. The roller 87 is adapted to co-operate with a cam 91 and the roller 88 with the cam 92, said cams being out of alignment as will be clear from Fig. 5. The cams 91 and 92 are mounted in the path of movement of the movable body such as the elevator and are shown in the drawings as being mounted on a suitable support 93 such as a portion of the elevator shaft being adjustably mounted thereon by means of the bolts 94 extending through the slots 95 and having their heads seated in recesses 96 in said members 91 and 92. Upon reference to Fig. 1, it will be seen that when the roller 87 engages with the bevelled face 97 of the cam 91 and rides upon the flat face 98 thereof, the lever 81 will be swung clockwise on the pivot 82, the rod or link 77 will be moved downwardly and the links 73 and 67 being keyed to the shaft 68 will act as a bell crank lever, the pivot being turned counter-clockwise with the shaft 68 thus moving the end of the link 64 pivoted on the pin 63 to the left in Fig. 1 and causing the contact member 49 to bridge the contacts 25 and 26.

In a similar manner, when the roller 88 rides up the inclined face 99 of the cam 92 and along the face 100 of said cam, the lever 81 will be moved in a counter-clockwise direction about the pivot 82, the link 77 will be moved upwardly swinging the lever comprising the members 73 and 67 in a clockwise direction, pulling on the link 64 so as to move the end thereof connected with the pivot pin 62 to the right and causing the contact member 49 to bridge the contacts 24 and 26. This action will occur no matter from what direction the movable body such as an elevator is approaching the cams 91 and 92. For example, in connection with the cam 92, the roller 88 will, if the elevator is below the cam 92, engage with the inclined face 101 of the cam 92 riding up the same

and then along the face 100 throwing the lever 81 again in a counter-clockwise direction and moving the movable contact 49 into engagement with the contacts 24 and 26.

When the parts are in the position shown in Fig. 1 in full lines, neither the roller 87 will engage with the cam 91 nor the roller 88 with the cam 92 and the parts will be held in a central position due to the action of the coil spring 102 which is a tension spring and which is secured at opposite ends to the pins 103 and 104 provided on the shoes 105 and 106 pivoted on the pivot member 82. The shoes are shown as being arcuate in shape and each is adapted to engage with a stop on the bracket 83, the shoe 105 being provided with a flange portion 107 engaging with the stop 108 on the bracket 83 and the shoe 106 being provided with a flange portion 109 engaging with a stop 110 on the bracket 83. Upon reference to Fig. 4, it will be seen that when the roller 87 rides up on the cam 91 and the lever 81 is thrown to an angular position with the end secured to the link 77 depressed below its normal position, the flange 109 will be engaged by the lever 81 moving the shoe 106 downwardly about the pivot 82 and extending the spring 102, the flange 107 engaging with the stop 108 to prevent movement of the shoe 105 with the shoe 106. Due to the tensioning of the spring, when the roller 87 leaves the cam 91, the parts will be restored to the position shown in full lines in Fig. 1.

In a similar manner, when the roller 88 engages with the cam 92, the shoe 105 will be moved upwardly while the shoe 106 will be held from upward movement due to engagement of the flange 109 with the stop 110 and the spring 102 will be tensioned so as to again restore the parts to a central position when the roller 88 leaves the cam 92. It is obvious that the spring 102 due to its centering of the lever 81 also holds the contacts 54 normally in engagement with the contacts 23 and 26 or in the position shown in full in Fig. 1. The lever 58 for actuating the contact member 35 is also normally held in an upright or central position by means of the weights 111 that are positioned on opposite sides of the extension 112 on the hub 62, thus tending to always return the lever to its open circuit position by the action of gravity.

The downward movement of the weights is limited by the stop flange 114 on the casting and it will be evident that upon actuation of the lever 58, one of said weights is lifted with the lever while the other is left in engagement with the flange 114, thus the weight turns the lever when the handle is released and moves the same until the weight strikes the flange 114 when the lever is in central position with the movable contact member 35 in an open circuit position.

It will be obvious that the cams 91 and 92 can be so located that neither the roller 87 nor the roller 88 will be in engagement with the cams when the floor of the elevator

5 car is in alignment with the floor of the building near which the cams 91 and 92 are located. It will also be evident from Fig. 1 that a very slight movement of the elevator car will cause either the roller 87 or the 10 roller 88 to engage with the cam 91 or the cam 92, the parts being shown in a dotted line position in Fig. 1 when the roller 87 engages with the cam 91.

It will also be obvious that the amount 15 of movement necessary to cause the actuation of the lever in either direction can be adjusted by adjusting the cams 91 and 92 by means of the bolt and slot connection between the same and the support 93. The 20 contacts 25 and 21 are the contacts that together with the contacts 26 and 22, control the movement of the elevator car in a downward direction, accordingly, if the controller handle 57 is moved to the right in Fig. 25 3, the car will travel downwardly or when the roller 87 engages with the cam 91, the car will travel downwardly, thus any movement of the car upwardly out of its position level with a floor due to a decrease in 30 the load on the elevator or any other cause will bring about the engagement of the cam 91 with the roller 87, closing the switch for moving the car downwardly through engagement of the contact 49 with the contact 25 bridging the contacts 25 and 26 and this movement will continue until the roller 87 leaves the cam 91 when the contact 49 will be restored to a central or open circuit 35 position by means of the spring 102. Should 40 the car move downwardly from its position level with the floor, the roller 88 will engage with the cam 92 and the contacts 24 and 26 will be bridged by the member 49 causing movement of the car in an upward 45 direction, the contacts 24 and 20 being the contacts for controlling the movement of the car upwardly. The movement of the lever 58 to the left obviously will also cause 50 an upward movement of the elevator car.

55 Due to the arrangement of the standard controller used with the car switch mechanism described above, it is immaterial that the rollers 87 and 88 will engage with the cams 91 and 92 as the elevator car passes floors at which no stop is to be made as the fact that the operator is holding the controller handle in such a position as to bridge either the contacts 20 and 22 or 113 or the contacts 21 and 22 or 113 will cause the 60 car to continue in the direction of movement in which it is proceeding due to the operator's handle of the car switch being held in such position and the means on the controller for preventing two circuits controlling 65 the operation of the motor in opposite di-

rections from being closed at the same time will prevent any interference by the mechanically operative movable contact member with the operation of the car by means of the regulation handle. Should the 70 handle, however, be thrown to a central position when either the roller 87 or 88 is opposite its cam at a certain floor, the mechanically or car controlled movable contact member will be immediately thrown to such 75 a position by the roller engaging with the cam, that the elevator car will be moved toward the landing or floor at which the cams are located, causing the car to travel until it reaches a level with said floor when the 80 current will be cut off by the mechanism being thrown to a central position due to the spring 102.

Having thus described my invention, what I desire to claim and secure by United 85 States Letters Patent is:

1. In an elevator control mechanism the combination with a car, of means for controlling the movement of said body comprising a switch having a manually movable 90 contact member and an independently movable contact member controlled in its movement by the movement of said body.

2. In an elevator control mechanism the combination with a car, of means for controlling the movement of said car comprising a switch having stationary contacts and a pair of movable contacts co-operating therewith, one of said movable contacts being manually operated and the other movable contact being automatically operated by the movement of said car in either upward or downward direction.

3. In an elevator control mechanism the combination with a car, of means for controlling the movement of said car comprising a switch having stationary contacts and a pair of movable contacts co-operating therewith, one of said movable contacts being manually operated and the other movable contact being automatically operated by the movement of said car, independently of 100 said manually operated contact.

4. The combination with a car body movable in an elevator shaft, of means for controlling the movement of said body comprising a switch having contacts controlling the movement of said body in one direction, contacts controlling the movement of said body in the opposite direction, a manually movable contact member adapted to close the circuit through either of said contacts and a movable contact, the position of which is controlled by the position of said movable body along said shaft adapted to close the circuit through either of said contacts.

5. The combination with a car body movable in an elevator shaft, of means for controlling the movement of said body comprising a switch having oppositely arranged 130

contacts controlling the movement of said body in one direction, oppositely arranged contacts controlling the movement of said body in the opposite direction, a manually 5 movable contact member adapted to close the circuit through either of said oppositely arranged contacts and a movable contact, the position of which is controlled by the position of said movable body along said shaft 10 adapted to close the circuit through either of said oppositely arranged contacts.

6. The combination with a car body movable in an elevator shaft, of means for controlling the movement of said body comprising 15 a switch having oppositely arranged contacts controlling the movement of said body in one direction, oppositely arranged contacts controlling the movement of said body in the opposite direction, a manually 20 movable contact member adapted to close the circuit through either of said oppositely arranged contacts and a movable contact, the position of which is controlled by the position of said movable body along said 25 shaft adapted to close the circuit through either of said oppositely arranged contacts, either of said movable contacts being movable independently of the other.

7. The combination with a car body movable in an elevator shaft past a landing station, of means for controlling the movement of said body comprising contacts controlling the movement of said body in opposite directions, a pair of movable contact 30 members, means for manually moving one of said movable contact members into circuit closing relation to said contacts and means for moving the other of said movable contact members into circuit closing relation to said 35 first contacts controlled by the position of said body relative to said station.

8. The combination with a car body movable in an elevator shaft past a landing station, of means for controlling the movement 40 of said body comprising contacts controlling the movement of said body in opposite directions, a pair of movable contact members, means for manually moving one of said movable contact members into circuit closing 45 relation to said contacts and means for moving the other of said movable contact members into circuit closing relation to said first contacts controlled by the position of said body relative to said station, said means 50 comprising a member for moving said movable contact member into circuit closing relation to the contacts controlling the movement of the body in one direction and a member for moving said movable contact 55 member into circuit closing relation to the contacts controlling the movement of the body in the opposite direction.

9. The combination with a car body movable in an elevator shaft past a landing station, of means for controlling the movement 60

of said body comprising contacts controlling the movement of said body in opposite directions, a pair of movable contact members, means for manually moving one of said movable contact members into circuit closing 70 relation to said contacts and means for moving the other of said movable contact members into circuit closing relation to said first contacts controlled by the position of said body relative to said station, said means being so mounted that said last mentioned movable contact member is in open circuit position when said body is in alignment with said station.

10. The combination with a car body movable in an elevator shaft past a landing station, of means for controlling the movement of said body comprising contacts controlling the movement of said body in opposite directions, a pair of movable contact members, means for manually moving one of said movable contact members into circuit closing 80 relation to said contacts and means for moving the other of said movable contact members into circuit closing relation to said first contacts controlled by the position of said body relative to said station, said means comprising a member for moving said movable contact member into circuit closing relation to the contacts controlling the movement of the body in the opposite direction, said members being 85 spaced apart vertically along said shaft so that neither of said members actuates said last mentioned movable contact member when said body is in alignment with said station.

11. A device of the character described comprising a rotatable shaft, an insulating support, stationary contact members on said support comprising portions on opposite sides of said support, means for rotating said shaft, a movable contact member co-operating with the stationary contact portions on one side of said support mounted on said shaft to rotate therewith, a contact member co-operating with the stationary contact portions on the opposite side of said support freely rotatably mounted on said shaft and means for moving said last mentioned contact member comprising a lever connected therewith, rollers thereon, and a pair of cams with which said rollers engage to move said lever in opposite directions.

12. A device of the character described comprising a rotatable shaft, an insulating support, stationary contact members on said support comprising portions on opposite sides of said support, means for rotating said shaft, a movable contact member co-operating with the stationary contact portions on one side of said support mounted 125

on said shaft to rotate therewith, a contact member co-operating with the stationary contact portions on the opposite side of said support freely rotatably mounted on said shaft and means for moving said last mentioned contact member comprising a lever connected therewith, rollers thereon, a pair of cams with which said rollers engage to move said lever in opposite directions, and 10 means for restoring said lever to a central position.

13. The combination with a car body movable in an elevator shaft past a landing station, of means for controlling the movement 15 of said body comprising a switch having a pair of movable contact members, said members each having means for normally holding the same in an open circuit position and being movable in opposite directions therefrom 20 to close the circuits controlling movement of said body in opposite directions, one of said movable contact members being manually operated and the other of said members being connected with a lever; rollers on said 25 lever, a cam engaging with one of said rollers to move said lever in one direction and another cam engaging with the other roller to move said lever in the opposite direction.

14. The combination with a car body movable in an elevator shaft past a landing station, of means for controlling the movement 30 of said body comprising a switch having a pair of movable contact members, said members each having means for normally holding the same in an open circuit position and being movable in opposite directions therefrom to close the circuit controlling movement of said body in opposite directions, one of said movable contact members being manually 35 operated and the other of said members being connected with a lever; rollers on said lever, a cam engaging with one of said rollers to move said lever in one direction and another cam engaging with the 40 other roller to move said lever in the opposite direction, said cams being located in said shaft near said station.

15. The combination with a body movable in a predetermined path past a station, of 45 means for controlling the movement of said body comprising a switch having a pair of movable contact members, said members each having means for normally holding the same in an open circuit position and being 50 movable in opposite directions therefrom to close the circuit controlling movement of said body in opposite directions, one of said movable contact members being manually operated and the other of said members being connected with a lever; rollers on said 55 lever, a cam engaging with one of said rollers to move said lever in one direction and another cam engaging with the other roller to move said lever in the opposite direction, 60 said cams being located in said path near 65

said station, neither of said cams engaging with said rollers when said body is aligned with said station.

16. The combination with a body movable in a predetermined path past a station, of 70 means for controlling the movement of said body comprising a switch having a pair of movable contact members, said members each having means for normally holding the same in an open circuit position and being movable in opposite directions therefrom to close the circuit controlling movement of said body in opposite directions, one of said movable contact members being manually 75 operated and the other of said members being connected with a lever, a cam engaging with one of said rollers to move said lever in one direction and another cam engaging with the other roller to move said lever in the opposite direction, said cams being located in said path near said station, and the engagement of either roller with its cam moving said lever in a direction to close the circuit controlling movement of the body 80 toward the station.

17. An elevator leveling mechanism comprising, in combination a car, a motor for raising and lowering the same, manually operable means on the car for controlling the operation of said raising and lowering 85 motor and control means for said motor automatically becoming operative when the manually operable means breaks the energizing circuit of the motor as the car approaches a landing to cause said motor to raise or lower the car until it is level with the landing.

18. An elevator leveling mechanism comprising, in combination a car, a motor for raising and lowering the same, manually 100 operable means on the car for controlling the operation of said raising and lowering motor and control means on said car automatically becoming operative when the manually operable means breaks the energizing 105 circuit of the motor as the car approaches a landing to cause said motor to raise or lower the car until it is level with the landing.

19. An elevator leveling mechanism comprising in combination a car, a motor for raising and lowering the same, manually 115 operable means on the car for controlling the operation of said raising and lowering motor, control means on said car automatically becoming operative when the manually operable means breaks the energizing circuit of the motor as the car approaches a landing, to cause said motor to raise or lower the car until it is level with the landing, and cam means adjacent the landings for rendering said second control means operative.

20. In a leveling device for electric elevators comprising a car, motor means for raising and lowering the car, a switch on said car for controlling the motor, said switch 120 125 130

having a hand control lever, a second lever for operating said switch, and means for operating said second lever comprising an arm connected thereto and pivoted on the 5 car and having cam engaging means thereon and cam members on the wall of the elevator well adapted to be engaged by said cam engaging means as the car passes, to cause said second lever to operate the switch and cause the motor to level the car at a landing when the hand control lever is moved into inoperative position.

In witness whereof, I hereunto subscribe my name this 3rd day of September, A. D. 1924.

JACOB D. SCHAKEL.
